UNITED STATES PATENT OFFICE.

FRANK J. MATOUSHEK, OF PRAIRIE DU SAC, WISCONSIN.

AEROPLANE SAFETY APPLIANCE.

Application filed November 7, 1921. Serial No. 513,461.

To all whom it may concern:

Be it known that I, FRANK J. MATOUSHEK, a citizen of the United States of America, residing at Prairie du Sac, in the county of Sauk and State of Wisconsin, have invented certain new and useful Improvements in Aeroplane Safety Appliances, of which the following is a specification.

This invention relates to certain new and useful improvements in safety appliances for aeroplanes and has particular reference to inflatable gas bags associated with the aeroplane wings and fuselage, the gas bags assisting the flotation of the aeroplane during flight thereof.

With the above general objects in view and others that will become apparent as the nature of the invention is better understood, the same consists of the novel form, combination and arrangement of parts herein-after more fully described, shown in the accompanying drawings and claimed.

In the drawings, wherein like reference characters designate corresponding parts throughout the several views,

Figure 1 is a top plan view of an aeroplane constructed in accordance with the present invention showing the gas bags associated with the aeroplane wings and fuselage,

Figure 2 is a cross sectional view taken on line II—II of Fig. 1 showing the manner of securing one of the gas bags to the aeroplane wing,

Figure 3 is a fragmentary longitudinal sectional view taken on line III—III of Fig. 1,

Figure 4 is a cross sectional view similar to Fig. 2 of a modified form of the invention showing the gas bag completely enclosing the aeroplane wing, and

Figure 5 is a detail sectional view taken on line V—V of Fig. 4.

Referring more in detail to the accompanying drawing there is illustrated an aeroplane embodying a fuselage 1 provided with a forwardly positioned motor driven propeller 2, rear vanes 3 and a steering rudder 4, the fuselage 1 having oppositely directed planes 5.

The planes designated by the numeral 5 may be flat as shown in the preferred form of my invention or they may be formed in any other desired shape suitable to act as a mount and shape retaining means for the inflatable gas bags. The general wing contour may be varied somewhat by changing the

design of the planes 5 but the principal use of these planes is to act as supports for the inflatable gas bags. The wing contour proper is formed by the inflatable gas bags and may be varied, as desired, by altering the form of the bags.

The inflatable gas bags associated with the planes and fuselage in the preferred form of the invention are shown more clearly in Figs. 1 to 3, the gas bag including a bottom wall 6 extending beneath the lower face of the plane 5 with side walls 7 extending upwardly and overlapping the upper edges of the plane while an end wall 8 overlaps the outer end of the plane. The upturned sides and ends of the bag have channel guides for receiving the edges of the plane and carry screw receiving attaching lugs 9 as clearly illustrated for anchoring the bag to the plane 5. A valve 10 is associated with each bag for supplying a gas thereto while spacing cords 11 limit the expansive movement of the bag relative to the plane. The inner ends of the bag adjacent the fuselage 1 are secured thereto by attaching tabs 12.

A similar gas bag is secured to the fuselage 1 intermediate the planes 5 and empennage 3, the bag 13 being positioned beneath the fuselage, extending above the same and being attached thereto as at 14, a filling valve being associated with the bag 13 similar to the valve for the plane bags 6. The gas bags associated with the plane and fuselage may be inflated as desired and will assist in the flotation of the aeroplane during flight.

A modified form of bag is shown in Figs. 4 and 5 wherein the bag walls 15 enclosing a central pocket formed of spaced walls 16 integral with the outer walls 15 and within which pocket the plane 5 of the wing is received, the bag being slidably mounted upon the plane from the outer end thereto and anchored thereto in any suitable manner, movement limiting cords 17 connecting the bag walls 15 and the pocket walls 16.

The gas bags may be constructed of any suitable material such as silk or rubber, and in one form of the invention the bags are positioned beneath the planes while in the other form of the invention the bags completely enclose the planes, the main idea in connection with the device being the provision of inflatable gas bags being associated with the planes and fuselage of an aeroplane.

2 While there are herein shown and described the preferred embodiments of the present invention, it is nevertheless to be understood that minor changes may be made therein without departing from the spirit and scope thereof.

What is claimed as new is:—

1. In an aeroplane having horizontally extending planes, inflatable gas bags surrounding said planes, a filling valve carried by each bag, and spacing cords provided in said bags for limiting the expansion of the same.
2. In an aeroplane having horizontally extending planes, inflatable gas bags surrounding said planes to afford proper wing contour, a filling valve carried by each bag, and spacing cords provided in said bags for limiting the expansion of the same.
3. In an aeroplane having horizontally ex-

tending planes, inflatable gas bags having central pockets formed therein, the said gas bags being slidably mounted upon the said planes and secured thereto, a filling valve carried by each bag, and spacing cords provided in said bags for limiting the expansion of the same.

4. In an aeroplane having horizontally extending planes, inflatable gas bags secured to said planes, the said bags comprising outer walls, inner walls formed integrally with said outer walls and spaced therefrom, said inner walls forming a central pocket adapted for receiving the planes, a filling valve carried by each bag, and spacing cords provided in said bags for limiting the expansion of the same.

In testimony whereof I affix my signature.

FRANK J. MATOUSHEK.
